STOP MOTION

Walter J. Scott, Woonsocket, R. I.

Application August 15, 1929. Serial No. 386,173

7 Claims. (Cl. 192—116.5)

The present invention relates to stop motions and has particular reference to electrically controlled stop motions suitable for use with textile machinery.

5 One object of the invention is to provide a stop motion which is normally held in inoperative position by a catch member and is released upon the closing of an electric stop circuit.

Another object is to provide a stop motion 10 having interengaging latch and catch members which disengage upon the making of an electric circuit and which break the electric circuit upon disengagement.

A further object of the invention is to provide 15 a movable catch member in an electric circuit which is automatically returned to locking position upon breaking of the circuit.

Other objects and advantageous features will be readily apparent from the detailed description 20 following, in conjunction with the accompanying drawing, and will be particularly pointed out in the appended claims.

In the drawing:

Fig. 1 is a view of the power control and the 25 stop mechanism therefor;

Fig. 2 is an enlarged view partly in section showing the stop mechanism locked in inoperative position;

Fig. 3 is a view similar to Fig. 2 showing the 30 members in position for release of the stop mechanism;

Fig. 4 is a perspective view of the catch member and its associated parts; and

Fig. 5 is a view, partly in section, on the line 35 5—5 of Fig. 2, showing the relative position of the catch and associated parts with respect to the armature.

It has been found desirable to construct a stop mechanism for textile machinery which is normally urged into operative position to stop the machinery, but is locked in inoperative position by a movable catch which releases the stop mechanism whenever an electric control circuit is completed. I have devised a stop mechanism 45 of this type in which the catch member and the cooperating latch member are also included in the electric circuit so as to break the circuit upon operative movement of the control mechanism, the catch member being automatically 50 returned to its normal locking position upon such breaking of the circuit; and the following is a detailed description of one constructional form of stop mechanism embodying the principle of my invention.

55 Referring to the drawing, 10 represents a power pulley of the usual type and 11 an idler pulley, mounted as shown on a common shaft 12. A belt shifter 13, secured to a shifter rod 14 which is suitably mounted for longitudinal movement, has a stop 15 adapted to be engaged by an op-

erating lever 16 for moving the belt shifter to stop the machine. The operating lever 16 is pivoted at 17, preferably to the frame of the machine, a spring 18 is fixedly secured to a stationary member or the like, as at 19, engaging the 65 operating lever to pull the lever in the direction to shift the belt shifter for stopping the machine. Secured to the operating lever 16 in any suitable manner, is a bracket 20 extending laterally therefrom and having a bifurcated end 21; a latch member 22 is pivotally mounted within said bifurcated end and has a stop 23 engaging the under side of the bracket 20, a spring 24 secured to the bracket member 20 and the latch member 70 serving to yieldingly maintain the latch member 75 in locking position.

An armature casing 25 is vertically positioned within a fixed arm or the like 26, within a suitable bore 27 therein, and is separated from the sides of the bore by insulation 28. The casing 80 is removably mounted within the bore, and is secured in position by any suitable means. Within the casing 25 are magnets 29, positioned as shown in Fig. 5, having suitable windings grounded at one end to the casing and secured to an 35 insulated contact pin or the like 30 at the other end, a lead wire 31 being fastened or secured in the usual manner to the contact pin 30.

Within the casing 27 is an armature plate 32 having a pin 33 extending through spaced ends 90 34 at one side, thereof, the pin 33 being pivotally mounted within the sides of the casing 27 to permit swinging of the armature plate in a vertical plane. A spring 35, secured to the plate 32 by riveting or in other suitable manner, normally tends to disengage the armature plate from the armature core upon breaking of the electric circuit. The side of the plate opposite the spaced ends 34 has a plurality of notches 36 formed therein which normally function as locking 95 notches for two arms 37 which are pivotally mounted in the sides of the casing by means of pins 38 extending therethrough.

A catch member 39 is positioned in the lower, open end of the casing, and has a rearward extending base 40, the base having two upwardly extending spaced ears 41 through which extends a pivot pin 42, the ends of the pin 42 being mounted in the sides of the casing and about which pin the catch member 39 is swingingly mounted so as to be engaged by the latch member 22. A coil spring 43 is mounted on the pin 42 and has outwardly extending ends 44 and 45 respectively contacting with the base 40 and the 105 rear of the casing 27 to normally force the catch member 39 downwardly into engagement with the latch member 22. The catch member 39 has two trunnions 46 extending laterally from the sides thereof, which trunnions bear on the 110 115 120

arms 37 and are normally received within notches 47 in the lower ends thereof.

As shown in Fig. 1, the electrical circuit includes the lead wire 31, the casing 27, the co-operating latch and catch members, the operating lever 16 and a switch 48 of any suitable type.

The operation of the improved stop mechanism is as follows:

The parts being in the position shown in Fig. 10, the switch 48 is closed, completing the electric circuit; the armature cores now attract and lift the armature plate 32, releasing the arms 37, and permitting the pull of spring 18, through the operating lever and the latch member, to move 15 the catch member and the arms, the upward swinging of the catch member against the compression of spring 43 releasing the latch member and permitting a lateral shifting of the belt shifter 13 to stop the machine. The separation of the catch and latch members breaks 20 the circuit, the armature plate 32 now swinging downwardly under the action of spring 35 and of gravity, the spring 43 forcing the catch member downwardly until the trunnions 46 enter 25 into notches 47, whereupon the arms 37 are swung back to their initial locking position, the catch member and associated parts now appearing as shown in Fig. 2. To start the machine again the shift rod 14 is shifted in the opposite 30 direction, thus moving operating lever 16 against the tension of spring 18 until latch member 22 engages with catch member 39 and turns against the tension of spring 24, the spring 24 swinging the latch member into locking engagement as 35 soon as the latch member clears the catch member. The stop mechanism is therefore again releasably held in locked position.

The above description is directed to a specific embodiment of a stop mechanism constructed in accordance with the principles of my invention, but changes within the limits of the claims hereto appended and adaptations to other types of machines may obviously be made without departing from the nature and spirit of the invention.

45 I claim:

1. A stop mechanism comprising a power stop, a bodily movable shift member for operating said power stop, means normally urging said member to operate the power stop, movable catch means releasably retaining said member against shifting, an electric circuit, an electromagnet in said circuit arranged to operate said catch means to release said shift member upon closing of the circuit, said shift member being included in said 50 circuit and arranged to move and break the circuit when released by said catch means, and means automatically returning said catch means to retaining position when said circuit is broken and said electromagnet is deenergized.

60 2. A stop mechanism comprising a power stop, a movable member for operating said power stop, yielding means normally urging said movable member to operate the power stop, a latch carried by said movable member, a movable catch releasably engaging said latch to hold the movable member in inoperative position, an electric circuit including the latch, the catch and the movable member, and an electromagnet in said circuit to operate when energized to move the catch to release the latch to permit said movable member to operate the power stop and simultaneously break the circuit to permit the catch to simultaneously return to normal.

3. A stop mechanism comprising a power stop, a movable member for operating said power stop, yielding means normally urging said movable member to shift its position, a pivoted spring pressed latch carried by said movable member, a movable catch releasably engaging said latch to hold the movable member in inoperative position, a spring for urging said catch to released position, locking means to maintain said latch in operating position, an electric circuit including the latch and the catch, and an electromagnet in said circuit to operate when energized to operate said locking means and permit the catch to move to release the latch and its movable member to operate the power stop and simultaneously break the circuit thus permitting the catch to automatically return to normal.

4. A stop mechanism comprising a power stop, a shifting member for operating said power stop, yielding means normally urging said shifting member to shift off the power, a latch on said shifting member, a catch mounted on a pivot pin arranged to assist in the support of the catch against the pull of the said shifting member and releasably engage said latch to hold the shifting member in inoperative position, an electric circuit including the latch and the catch, an electromagnet in said circuit controlling the release movement of the catch to release the latch on closing of the circuit and thus break the circuit, and means automatically returning said catch means to locking position upon breaking of the circuit.

5. In a stop mechanism, an insulated casing, an electromagnet therein, a locking armature plate pivotally mounted adjacent said electromagnet to be moved to unlocked position when said electromagnet is energized, a release arm pivotally mounted at one end and locked against movement by said plate when said plate is in operating position, a movable catch, means for locking said catch in operating position when said arm is locked, and means normally urging said catch and said arm into locking position.

6. In a stop mechanism, an insulated casing, an electromagnet therein, an armature plate pivotally mounted adjacent said electromagnet for vertical swinging movement to released position by action of the magnet, a pivotally mounted arm locked against release movement by engagement with said plate when said plate is in operative position, said arm having a lock notch therein, a movable catch, lateral extensions thereon adapted to seat in said lock notch, and a spring normally urging said catch in a direction to seat the extensions in said lock notches and move the arms and the catch to locking position.

7. A stop mechanism comprising a power stop, a movable member for operating said power stop, yielding means normally urging said movable member to operate the power stop, a pivoted latch movable with said movable member, a movable catch releasably engaging said latch to hold the movable member in inoperative position, an electric circuit including the latch and the catch and movable member, and an electromagnet in said circuit to operate when energized to move the catch to release the latch to permit said movable member to operate the power stop and simultaneously break the circuit and permit the catch to return to normal.

WALTER J. SCOTT.
